CLAIM

The ornamental design for a vehicle armrest as shown and described.

DESCRIPTION

FIG. 1 is a front, left and top perspective view of the vehicle armrest showing our new design;

FIG. 2 is a front elevational view thereof;

FIG. 3 is a rear view thereof;

FIG. 4 is a left side view thereof

FIG. 5 is a right-side elevational view thereof;

FIG. 6 is a top plan view thereof;

FIG. 7 is a bottom plan view thereof; and,

FIG. 8 is a perspective view of the vehicle armrest in use. The dash-dot-dash broken line showing of a door and a seat is included for the purpose of illustrating environmental structure and forms no part of the claimed design.
